(57) **CLAIM**

The ornamental design for a faucet as shown and described.

DESCRIPTION

FIG. 1 is a front perspective view of a first embodiment of a faucet showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a second front perspective view thereof;

FIG. 9 is a rear perspective view thereof;

FIG. 10 is a front perspective view of a second embodiment thereof;

FIG. 11 is a front view of FIG. 10;

FIG. 12 is a rear view of FIG. 10;

FIG. 13 is a side view of FIG. 10;

FIG. 14 is an opposite side view of FIG. 10;

FIG. 15 is a top view of FIG. 10;

FIG. 16 is a bottom view of FIG. 10; and,

FIG. 17 is a second perspective view of FIG. 10.

The features presented in broken lines illustrate portions of the faucet that form no part of the claimed design.

1 Claim, 13 Drawing Sheets
